UNITED STATES PATENT OFFICE.

DAVID F. STAUFFER, OF YORK, PENNSYLVANIA.

DESIGN FOR A CRACKER.

SPECIFICATION forming part of Design No. 16,849, dated August 10, 1886.

Application filed March 29, 1886. Serial No. 1,7,044. Term of patent 14 years.

To all whom it may concern:

Be it known that I, DAVID F. STAUFFER, a citizen of the United States, residing at York, in the county of York and State of Pennsylvania, have invented a new and original Design for Crackers or Pretzels, of which the following is a specification, reference being had to the accompanying drawings, forming part thereof.

10 In the said drawings, Figure 1 represents a perspective view of my newly-designed cracker or pretzel; Fig. 2, a longitudinal sectional view of the same, and Fig. 3 a transverse sectional view thereof.

15 The leading feature of my design consists of an oblong cracker or pretzel, elliptical in cross-section or approximating thereto, having its ends corrugated, scalloped, or crimped, as shown in the respective figures of the draw-

20 ings.

In the drawings, the letter A indicates the

cracker or pretzel, which is oblong in shape and elliptical in cross-section, and which has its ends corrugated, crimped, or scalloped, as indicated by the letter B in said drawings. 25 It will be observed that the cracker or pretzel in its general contour, taken in longitudinal section, is oblong, and at the ends is rounded. The said rounded ends are crimped in lines diverging outwardly, which give the article a 30 highly-attractive appearance.

I claim—

The design for a cracker, the same consisting of an oblong body elliptical in cross-section, and having its ends rounded and crimped 35 or corrugated in outwardly-diverging lines, as described and shown.

D. F. STAUFFER.
